CARTON

Paul F. Vandervort, Canton, Ohio, assignor to
General Container Corporation, Cleveland,
Ohio, a corporation of Ohio

Original application July 5, 1938, Serial No.
217,461. Divided and this application July 12,
1940, Serial No. 345,122

2 Claims. (Cl. 229—23)

The invention relates to cartons, and more particularly to corrugated paper cartons, and the present application is a division of my prior application for Bicycle cartons, Serial No. 217,461, filed July 5, 1938.

The object of the invention is to provide a carton in which the side and end walls are provided at their upper and lower edges with angular, outturned flanges to which the edge portions of the top and bottom walls are attached, as by stitching, thus strengthening and reinforcing the carton.

Another object is to provide such a carton in which the side walls have angular, outturned flanges extending the entire length of their upper and lower edges, and the end walls having flanges at their upper and lower edges extending beyond the ends of the wall, and angular flanges at opposite ends separated from the upper and lower flanges by notches, and connected to the end portions of the side walls.

The above objects together with others which will be apparent from the drawing or which may be later referred to may be attained by constructing the improved carton in the manner illustrated in the accompanying drawing, in which:

Figure 1 is a plan view of a carton constructed in accordance with the invention and showing a bicycle packed therein, the cover or top wall being removed;

Fig. 2, an enlarged fragmentary elevation of one corner portion of the carton;

Fig. 3, an enlarged section through one end or side of the carton;

Fig. 4, a plan sectional view through one corner portion of the carton;

Fig. 5, an enlarged elevation of the pad which receives the saddle post and steering post of the bicycle; and

Fig. 6, an elevation of one of the blanks from which an end wall of the carton is formed.

Similar numerals refer to similar parts throughout the several views.

The improved carton to which the invention pertains is made up of the side and end walls, 10 and 11, respectively, of a width sufficient to substantially, snugly accommodate the bicycle to be packed, the bottom wall 12, and the top wall or cover 13, both of which may be in the form of flat sheets. All of these parts are preferably formed of corrugated paper or board.

The end walls 11 are provided at their ends with angular flanges 14 adapted to be bent around the adjacent end portions of the side

walls 10, and connected thereto as by stitching or staples indicated at 15.

Outturned, angular flanges 16 and 17 are formed at the upper and lower edges respectively of the side walls 10 and end walls 11.

The side walls 10 are of elongated, rectangular shape, the flanges 16 and 17 thereon extending the entire length of each side wall. The end walls 11 are formed from blanks of a shape as shown in Fig. 6, the upper and lower flanges 16 and 17 thereof being cut off at each end at points spaced from the outer edges of the flange portions 14, and being separated from the upper and lower ends of the flanges 14 by the notches 11a.

With this construction of end wall it will be seen, as shown in Fig. 1, that the ends of the flanges 16 and 17 of the end walls extend beyond the ends of said end walls and are in line with the side edges of the flanges 16 and 17 of the side walls, thus forming a rectangular flange formation of the same size and shape as the top and bottom walls which are connected thereto.

The bottom wall 12 is attached around its edge portions to the lower flanges 17 as by the stitching or staples shown at 18.

After the bicycle has been properly packed within the carton the top wall 13 may be similarly connected to the upper flanges 16 as indicated at 19.

30 The bicycle shown in the carton in Fig. 1 comprises, generally, the frame 20 having the saddle post 21 and the steering post 22, and the front and rear wheels 23 and 24, respectively.

The carton is preferably of such dimensions 35 that the bicycle will fit substantially, snugly therein, and when properly packed with the blocks and pads forming a part of the invention, will be held against movement within the carton.

At each lower corner of the carton is located 40 a pad comprising a right angle strip 25 of corrugated paper or the like having spaced pairs of pads or blocks 26 located at its end portions and providing slots adapted to receive the wheels of the bicycle. These pads need not be attached 45 to the carton but are held in place by the bicycle.

A pair of triangular wheel blocks 27 formed of corrugated paper or the like are connected to opposite ends of a sheet 28 which is located against the adjacent side wall of the carton and 50 between the ends of the angular sheets 25, the blocks 27 contacting with the tires of the front and rear wheels of the bicycle.

The saddle 29 may be removed from the bicycle and located within a box like holder 30 attached to the sheet 28 and having one end out

and the flap thus formed turned out as at 31 to receive the smaller end of the saddle.

A triangular wheel block 32 may be fixed upon one end of a corrugated sheet 33 which fills the space between the adjacent end of the angular sheet 25 at the forward end of the bicycle and the opposite side wall 18 of the carton.

The corrugated sheet 34 is provided at opposite ends with spaced pairs of blocks 35 and 36, the slots 37 and 38 formed therebetween being closed at their ends as at 40.

The saddle post 21 is received in the slot 37 between the blocks 35 and the steering post 22 is received in the slot 38 between the blocks 36, and since the ends of these slots are closed the sheet 34 with the blocks 35 and 36 thereon is held against relative movement within the carton.

If desired, a filler in the form of a rectangular open-ended box 41, and of a height equal to the distance between the bottom and top walls 12 and 13 may be located within the frame of the bicycle and may be reinforced as by the diagonal partition wall 42.

After the bicycle has been packed in the carton as illustrated in Figure 1 and in the manner above described, the top wall 13 may be placed thereon and stitched or stapled around its edges to the flanges 16 at the upper edges of the side and end walls 10 and 11 as by the staples 19, thus completely enclosing the bicycle within the carton, protecting it against the weather as well as against accidental marring and holding the bicycle tightly packed against relative movement within the carton.

Although interior packing devices are illustrated and described for the purpose of packing a bicycle in the carton, these devices form no part of the present invention as they are claimed in the parent application, Serial No. 217,461, above referred to, and any other form of interior packing device for packing a bicycle, or other article, may be used in the carton disclosed here-

in, the particular construction of said carton forming the subject matter of the present invention, which may be used either with or without interior packing devices.

5 I claim:

1. A carton formed of corrugated paper including elongated rectangular side walls having outturned, angular flanges at their upper and lower edges and co-extensive therewith, end 10 walls having angular flanges at their ends lapped over and connected to the adjacent end portions of the side walls, and outturned angular flanges at their upper and lower edges of greater length than the end walls and terminating at the ends 15 of the upper and lower flanges of the side walls in outwardly disposed ends located in the same planes as the body portions of said outturned angular flanges, and rectangular top and bottom walls having their edge portions overlying and 20 stitched to said upper and lower angular flanges respectively of the side walls and end walls including outwardly disposed ends of the latter flanges.

2. A carton formed of corrugated paper including elongated rectangular side walls having outturned, angular flanges at their upper and lower edges and co-extensive therewith, end walls having angular flanges at their ends lapped over and connected to the adjacent end portions of the side walls, and outturned angular flanges at their upper and lower edges of greater length than the end walls and terminating at the ends 30 of the upper and lower flanges of the side walls in outwardly disposed ends located in the same planes as the body portions of said outturned angular flanges and separated from the angular end flanges by notches, and rectangular top and bottom walls having their edge portions overlying and 35 stitched to said upper and lower angular flanges respectively of the side walls and end walls including the outwardly disposed ends of the latter flanges.

PAUL F. VANDERVORT.
